United States Patent

Des. 239,683
Patented Apr. 27, 1976

239,683

CHAIR

Paul Tuttle, Santa Barbara, Calif., assignor to Intercollection Development S.A., Kirchberg, Switzerland

Filed Jan. 2, 1975, Ser. No. 538,166

Term of patent 14 years

Int. Cl. D6—01

U.S. Cl. D6—49

FIG.1

FIG.2

FIG.3

FIG.4

FIG.5

FIG.6

FIG. 1 is a perspective view showing the top, front and side of the chair embodying my new design;

FIG. 2 is a top plan view;

FIG. 3 is a front elevational view;

FIG. 4 is a side elevational view of the side opposite to that shown in FIG. 1;

FIG. 5 is a rear elevational view; and

FIG. 6 is a bottom plan view.

I claim:

The ornamental design for a chair, as shown.
